[57] CLAIM

The ornamental design for a bottle or similar article, substantially as shown and described.

DESCRIPTION

FIG. 1 is an elevational view of a bottle or similar article showing our new design, the opposite side being the same in appearance;

FIG. 2 is an elevational view taken from the right of FIG. 1, the opposite side being the same in appearance;

FIG. 3 is a bottom plan view; and

FIG. 4 is a top plan view thereof.

FIG. 1

FIG. 2

FIG. 4
